UNITED STATES PATENT OFFICE.

GIUSEPPE BANDIERI, OF CINCINNATI, OHIO.

ELECTRIC ADVERTISING APPARATUS.

No. 922,836.

Specification of Letters Patent. Patented May 25, 1909.

Application filed April 30, 1908. Serial No. 430,073.

To all whom it may concern:

Be it known that I, GIUSEPPE BANDIERI, residing at Cincinnati, in the county of Hamilton and State of Ohio, have invented a certain new and useful Improvement in Electric Advertising Apparatus, of which the following is a full, clear, and exact description, reference being had to the accompanying drawings.

10 This invention relates to electrical advertising devices, that is to say, devices wherein advertising matter is illuminated for predetermined intervals by electrically operating means.

15 More limitedly, the invention relates to advertising apparatus wherein a film or ribbon having advertising matter thereon arranged at suitable intervals is fed past a source of light, the feeding of the film or ribbon being suspended when the matter to be illuminated is in proper relation to the light, the illumination being effected during the cessation of the feeding of the film or ribbon. Means are provided whereby, when the film 25 or ribbon has been wound or fed off the drum on which it is carried, it will be automatically rewound upon said drum.

One form of apparatus for carrying out my invention is illustrated in the drawings forming a part hereof, wherein—

Figure 1 represents a somewhat diagrammatic elevation of my invention, showing the same arranged within a cabinet or casing, one wall of the casing being removed; Fig. 2 35 represents a front elevation, on a reduced scale, of the device shown in Fig. 1; and Fig. 3 represents a detail of the film or ribbon, illustrating the connections by which the same is wound in reverse directions.

40 Describing the parts by reference characters, 1 denotes the casing having in the front thereof a suitable aperture 2, which may be provided with a glass or other transparent medium 3 for the inspection of the advertising matter. Within the casing there is mounted a drum 4 from which the ribbon or film 5 is fed. This drum is provided with a pulley 6, by means of which and a belt 7 the drum may be rotated from an electric motor 50 8, of any approved construction.

9 denotes a guide roller mounted in the front of the casing, over which the ribbon or film passes on its way to the tension roller 10 mounted near the lower front of the casing. 55 From roller 10 the ribbon or tape passes to the drum 11. Roller 10 is preferably a heavy

metallic roller the journals 10^a whereof are mounted in slots 12 in a metallic frame 13.

Drum 11 is provided with an operating gear or roller 12, which gear or roller is preferably of the friction type, having its periphery provided with leather or hard rubber. Gear or roller 12 is driven by means of a continuously rotating mutilated gear 14. This mutilated gear is mounted upon a shaft 15, which may be rotated continuously from any convenient source of power, for instance, a clockwork mechanism, as indicated at X in Fig. 1. At its outer periphery, the gear is provided with a suitable number of toothed segments 16, which are preferably detachably mounted upon a drum of insulated material and are spaced apart by recesses. Any suitable number of such segments may be provided, depending upon the circumstances of each particular case. The parts are so arranged that the toothed segments will engage the periphery of gear or roller 12 and thereby rotate the drum 11 in a direction to wind thereon the film or ribbon 5 and feed such film or ribbon from drum 4 onto drum 11. It will be apparent that, when the toothed segments pass out of engagement with gear 12, rotation of drum 11 and the feeding of the film or ribbon will be suspended.

17 denotes a series of incandescent lamps arranged opposite the sight opening 2 and directly at the rear of the film or ribbon 5. For the purpose of automatically winding the ribbon or film back upon the drum 4 when it has been unwound therefrom as far as advisable as well as for illuminating the lamps during an inactive period of said film or ribbon, the following construction is provided:

18 and 19 denote a pair of electro-magnets, the armatures 20, 21 whereof respectively are carried by a lever 22 which is pivoted at 22' above and between said magnets. Lever 22 is a circuit-opening and closing device and has its opposite ends provided with terminals 23 and 24 adapted to electrically contact with terminals 25 and 26 respectively. The last-mentioned terminals may be mercury cups wherein the lower ends of terminals 23 and 24 may dip, or may be of any other suitable form of switch members.

A and B represent respectively the positive and negative main-line conductors through which current is supplied to the apparatus for the purpose of operating the same. Conductor A is connected to the

winding of magnet 19 by means of a suitable wire 27. The opposite end of said winding is connected with wire 28, which is connected with spring 29. This spring presses 5 against the film or ribbon and, but for the presence of said film or ribbon, would be in contact with roller 10. This roller, as previously stated, is of metal and its journals are in electrical contact with frame 13. 10 Frame 13 is connected directly to the negative conductor B by means of wire 30. Conductor A is also connected with lever 22 by means of wire 31 which may connect with wire 27. Terminal 26 is connected by means 15 of wire 32 with a spring 33, the upper end of which presses against a drum 34 mounted upon shaft 15. Drum 34 is preferably of non-conducting material and is provided on its periphery with conducting segments 35 20 which are electrically connected with shaft 15 and thus, in turn with the frame 36 in which said shaft is journaled. The segments 35 correspond in location to the recessed portions of the drum 14, which are 25 unprovided with segments 16. Frame 36 is connected by a wire 37 with one side of the lamps 17. Wire 38, which is connected with the opposite side of said lamps, is connected with the negative conductor B. 30 39 denotes a contact ring which is carried by drum 14 and is engaged by the upper end of a spring 40. This ring is provided with an inwardly projecting member 41 which is adapted to engage the upper end of a second 35 spring 42. Spring 40 is connected with the main line conductor A by wire 43. Spring 42 is connected by a wire 44 with one end of the winding of electro-magnet 18. The opposite end of said winding is connected by a 40 wire 45 with the spring 46, which is arranged in a similar manner to spring 29 and is prevented from contacting with roller 10 by means of the film or ribbon 5. Through frame 13 and wire 30, spring 46 is connected 45 with the negative main line conductor B.

By reference to Fig. 3, it will be seen that the film or ribbon 5 is provided with two elongated apertures therein, 47 and 48. The former aperture is located near the end of the 50 film or ribbon that is fastened to drum 11; the latter aperture is located near the end of the film or ribbon that is fastened to drum 4. The distance between these apertures is so predetermined that, when aperture 48 is under spring 46, contact 41 will be in engagement with spring 42.

With the parts arranged as described, the operation will be as follows: Drum 14 will 60 rotate, thereby rotating drum 11 in a direction to feed the film or ribbon a distance predetermined by the length of a segment 16. This distance will be sufficient to remove from in front of aperture 2 the advertising matter that has been there before 65 and to bring before said opening a new illus-

tration or legend. As soon as segment 16 passes off the gear or roller 12, spring 33 engages one of the conducting segments 35. This closes the lighting circuit through 27, 31, 22, 24, 26, 32, spring 33, contact 35, 70 frame 36, conductors 37 and 38. Simultaneously with the breaking of this circuit by the spring 33 passing off contact 35, another toothed segment engages roller 12, rotates drum 11, advancing the ribbon or 75 film another step. This operation continues until the ribbon or film is practically entirely wound off the drum 4. At this period, the motor circuit is closed as follows: The parts are so timed that, when spring 46 can engage roller 10 through the elongated slot 48, contact 41 is beneath spring 42. This closes the circuit from A through wire 43, spring 40, contact 41, spring 42, wire 44, winding of electro-magnet 18, wire 45, spring 46, 80 roller 10, frame 13, wire 30 and line conductor B. Closing this circuit causes the electro-magnet 18 to attract its armature and closes the circuit between 23 and 25. This closes the motor circuit from conductor A through wires 27, 31, lever 22, contacts 23 and 25, wires 49 and 50. This closing of the motor circuit occurs just after the engagement of spring 33 with the contact 35, and the motor rapidly winds the 85 ribbon back upon the drum 4 until such time as spring 29 can engage roller 10 through aperture 47, whereupon the circuit through winding of electro-magnet 19 is closed, which causes said magnet to attract 90 its armature 21 and break the circuit at 23, 25. From the construction and arrangement of parts, it will be seen that no current flows through the windings of magnets 18 and 19 except only at such times as the apertures 95 47 and 48 are opposite springs 29 and 46 and the tension roller 10. The lever 22 is in stable equilibrium so that, when the circuit through a magnet winding is broken, it will remain in position to close the circuit 100 at 24—26 or 23—25, according to whichever magnet was last energized. Furthermore the motor circuit is closed only from the time that the aperture 48 comes beneath 105 spring 46 until aperture 47 comes beneath 110 spring 29. At this time, the lighting circuit, which includes contacts 24—26, is broken. The parts should be so arranged that illumination will be given to the last legend or device upon the film or ribbon before the 115 motor is placed in operation. This can be done by suitably proportioning and arranging contacts 35 and 41 and aperture 48, so that spring 33 will engage the contact 35 shortly in advance of the engagement of 120 spring 42 by contact 41 and the engagement of roller 10 by spring 29 through aperture 48. 125

The rewinding operation is timed so as to take place entirely within the space of time during which the teeth upon the mutilated 130

gear are not in contact with the feed roller. The apertures 47 and 48 upon the film are so arranged that the motor will be started and stopped while the feed roller is disengaged from the mutilated gear.

From the above description, it will be apparent that I have provided an apparatus which, while comparatively simple and inexpensive of construction, will automatically 10 effect the intermittent feeding of the ribbon or film, will automatically illuminate the advertising matter on said film or ribbon during the inactive period of the feeding mechanism, and which will automatically 15 wind the film or ribbon back upon its drum after the last legend or device thereon has been displayed.

Having thus described my invention, I claim:

20 1. In an advertising apparatus, the combination of a casing having a sight opening therein, a drum arranged at one side of said opening, a feed roller arranged at the opposite side of said opening, a film or ribbon extending between said roller and drum, a tension device for said film or ribbon, one or more lamps within said casing and arranged to illuminate the portion of the film or ribbon which is in proximity to said opening, means 25 for rotating said feed roller intermittently to feed the film or ribbon past the sight opening, and means for automatically quickly and continuously rewinding the ribbon from the feed roller upon the drum.

30 2. In an advertising apparatus, the combination of a casing having a sight opening therein, a drum arranged at one side of said opening, a feed roller arranged at the opposite side of said opening, a film or ribbon extending between said roller and said drum, a tension device for said film or ribbon, one or more lamps within said casing and arranged to illuminate the portion of the film or ribbon which is in proximity to said opening, means 35 for rotating said feed roller intermittently to feed the film or ribbon past the sight opening, a motor for automatically rewinding the ribbon from the feed roller upon the drum, and a circuit including said tension device for 40 causing said motor to operate.

35 3. In an electric advertising apparatus, the combination of a drum, a feed roller, a ribbon extending therebetween and connected thereto, a motor connected to said drum, one or more electric lamps for illuminating said film or ribbon, a device for rotating said feed roller intermittently to produce intermittent feeding of said film or ribbon, means controlled by said device for 45 closing a circuit through said lamp or lamps, and means also controlled by said device for closing the motor circuit when the film or ribbon has been wound off the drum a predetermined distance.

65 4. In an electrical advertising apparatus,

the combination of a drum, a feed roller, a film or ribbon extending between and connected to said drum and roller, a motor connected to said drum, one or more electric lamps for illuminating said film or ribbon, a 70 rotating member adapted to rotate said roller intermittently, connections whereby said member will close the lamp circuit during an inactive period of the roller, and connections whereby said member will close the motor 75 circuit when the film or ribbon has been unwound from the drum a predetermined distance.

5. In an electrical advertising apparatus, the combination of a drum, a feed roller, a 80 film or ribbon extending therebetween and connected thereto, a motor for operating said drum, one or more electric lamps for illuminating said film or ribbon, a mutilated gear adapted to rotate said roller intermittently, 85 and circuit-closing means carried by said gear for causing said lamp or lamps to be lighted during an inactive period of said roller and for closing the motor circuit when the film or ribbon has been wound a predetermined distance by the roller.

6. In an electrical advertising apparatus, the combination of a drum, a feed roller, a 90 film or ribbon extending therebetween and connected thereto, a mutilated gear adapted to operate said roller to rotate the same intermittently, an electric motor connected with said drum, one or more lamps for illuminating said film or ribbon, electrical circuits including said motor and said lamp or lamps, 100 and contact devices carried by said gear for making and breaking said circuits.

7. In an electrical advertising apparatus, the combination of a drum, a feed roller, a ribbon extending between said drum and 105 said roller and connected thereto, an electric motor for operating said drum, a constantly rotating device having means for operating said roller intermittently, one or more electric lamps for illuminating said film or ribbon, electrical circuits including said motor and said lamp or lamps, and contact devices carried by the roller operating device and adapted to close the lamp circuit during the intervals of rest of said roller and to close 110 the motor circuit when the ribbon or film has been wound upon the roller to a predetermined extent, the lamp or lamps being extinguished when the motor circuit is active.

8. In an electrical advertising apparatus, the combination of a drum, a feed roller, a tension roller interposed between said drum and feed roller, a ribbon or film connected to said drum and said roller and passing around 125 said tension roller, a contact spring pressing against the ribbon or film and against said tension roller, an electric motor operatively connected with said drum, means for rotating the feed roller, and an electric circuit in- 130

cluding said motor and said spring and tension roller, said film or ribbon being provided with an aperture through which the spring may contact with said tension roller 5 to complete the motor circuit when the ribbon or film has been wound to a predetermined extent on the feed roller.

9. In an electrical advertising apparatus, the combination of a drum, a ribbon or film 10 operatively connected thereto and mounted thereon, means for feeding said ribbon or film intermittently from said drum, one or more lamps for illuminating said ribbon or film, an electric motor connected with said 15 drum, electric circuits one circuit including said lamp or lamps and the other circuit including said motor, each circuit including an electro-magnet, an armature therefor, and a switch mechanism operated by said armature, said switch mechanism being arranged to close the lighting circuit while opening the motor circuit and vice versa.

10. In an electrical advertising apparatus, the combination of a drum, a ribbon or film 25 operatively connected thereto and mounted thereon, means for feeding said ribbon or film intermittently from said drum, one or more lamps for illuminating said ribbon or film, an electric motor connected with said 30 drum, an electric circuit including said lamp or lamps, a second circuit including said motor, a pair of electro-magnets, an armature lever pivoted between said magnets and having circuit making and breaking devices 35 arranged at opposite sides of its pivot arranged to close the lighting circuit while opening the motor circuit and vice versa.

11. In an electrical advertising apparatus, the combination of a drum, a feed roller, a 40 ribbon or film extending therebetween, means for rotating said roller intermittently, said means comprising a friction roller connected with the former roller and a rotatable member having its periphery provided with 45 gear segments adapted to engage said friction roller, with recesses intermediate between said segments, a circuit-closing device rotatable with said gear segments, said device comprising a drum having on its periphery conducting strips interposed between said gear segments, a contact member arranged to engage said strips, and a lamp circuit including said contact member and said conducting strips.

55 12. In an electrical advertising apparatus, the combination of a drum, an electric motor connected thereto, a feed roller, a film or ribbon extending between said drum and roller and connected thereto, said film or ribbon having adjacent each end thereof an elongated slot, means for rotating said roller intermittently, a circuit operative when one of said slots is in a certain position including 60 said motor for operating said drum, and a

circuit operative when the other of said slots 65 is in a certain position, for breaking the motor circuit.

13. In an electrical advertising apparatus, the combination of a drum, an electric motor connected thereto, a feed roller, a film or ribbon extending between said drum and roller and connected thereto, a tension roller having a conducting surface and interposed between said drum and the former roller and over the surface of which the film or ribbon 70 passes, a pair of contact springs pressing against said film or ribbon pressing the same against said roller, said film or ribbon being provided with a pair of spaced apertures, means for operating the feed roller periodically, and an electric circuit for starting and stopping said motor, said circuit comprising a pair of electro-magnets, an armature lever pivoted therebetween, said lever being provided at one end with a contact for closing 80 the motor circuit, and circuits including said springs and the windings of said magnets for closing the motor circuit when one of said apertures comes between its spring and the tension roller and for breaking the motor circuit when the other aperture comes between 85 the other spring and the tension roller.

14. In an electrical advertising apparatus, the combination of a drum, an electric motor connected thereto, a feed roller, a film or ribbon 90 extending between said drum and roller and connected thereto, a tension roller having a conducting surface and interposed between said drum and the former roller and over the surface of which the film or ribbon 95 passes, a pair of contact springs pressing against said film or ribbon and pressing the same against said roller, said film or ribbon being provided with a pair of spaced apertures, means for operating the feed roller periodically, and an electric circuit for starting 100 and stopping said motor, said circuit comprising said springs.

15. In an electrical advertising apparatus, the combination of a drum, a feed roller, a 110 ribbon extending between said drum and roller and connected thereto, means for operating said roller, said means comprising a rotating gear adapted to operate the feed roller to rotate the same, a motor for operating said drum, a contact ring rotating with said gear, a pair of contacts, one of said contacts engaging said contact ring, a projecting lug or finger carried by said ring and adapted 115 to engage the other spring, and an electric circuit for operating said motor, said circuit including said contacts.

16. In an advertising apparatus, the combination of a drum, a feed roller, a film or ribbon extending between said drum and said roller, means for intermittently feeding the film or ribbon from the drum onto the roller, means for illuminating said film or 125

ribbon during an inactive period of the feed roller, and means for automatically rewinding the ribbon quickly and continuously from the feed roller upon the drum.

5 17. In an advertising apparatus, the combination of a drum, a feed roller, a film or ribbon extending between said drum and said roller, means for intermittently feeding the film or ribbon from the drum onto the 10 roller, means for illuminating said film or ribbon during an inactive period of the feed roller, and means for automatically rewinding the ribbon quickly and continuously from the feed roller upon the drum, the said 15 illuminating means being non-operative during the entire rewinding operation.

18. In an advertising apparatus, the combination of a drum, a feed roller, a film or ribbon extending between said drum and said roller, means for intermittently feeding the film or ribbon from the drum onto said roller, means for illuminating said film or ribbon during an inactive period of the feed roller, a motor connected to said drum, and means 20 for automatically causing said motor to operate to quickly and continuously rewind the 25

ribbon upon the drum after a predetermined part of said ribbon has been unwound.

19. In an advertising apparatus, the combination of a drum and a feed roller, a film or ribbon extending between said drum and ribbon and connected therewith, a constantly rotating mutilated gear adapted to operate said roller intermittently, a lamp or lamps for illuminating said film or ribbon, a circuit controlled by said mutilated gear for causing said lamp or lamps to illuminate only during an inactive period of the film, a motor connected to said drum, a circuit including said motor for automatically causing the 30 motor to operate and to quickly and continuously rewind the ribbon upon the drum, said circuit being operative only after a part of said ribbon has been unwound, said illuminating means being non-operative during the 35 rewinding operation.

In testimony whereof, I hereunto affix my signature in the presence of two witnesses.

GIUSEPPE BANDIERI.
